UNITED STATES PATENT OFFICE.

GIROLAMO RAGUSA, OF PUEBLO, COLORADO.

AUTOMATIC SIGNAL.

Application filed January 31, 1927. Serial No. 164,865.

The object of the invention is to provide a signal, automatically operated, wherein not only the warning may be indicated at the time of actuation, but an obstacle 5 interposed to the passage of the traffic against which the signal has been set; to provide a signal particularly adapted for railroad crossings that will be set into operative position by the passage of a train and 10 automatically returned to inoperative position after said train has passed; to provide yielding anchoring means in connection with the device so that, in the event that it is subjected to shock, it may not be damaged 15 thereby; and to provide a signal equipment which is susceptible of construction out of standard stock and, therefore, possible of manufacture and installation at low cost.

With this object in view, the invention 20 consists in a construction and combination of parts of which a preferred embodiment is illustrated in the accompanying drawings, wherein:

Figure 1 is a front elevational view of the 25 invention, the receiving pit below the surface of the ground being indicated in section.

Figure 2 is a side elevational view, partly 30 in section.

Figure 3 is a horizontal sectional view on 35 the plane indicated by the line 3—3 of Figure 1.

Figure 4 is a vertical sectional view on 40 the plane indicated by the line 4—4 of Figure 2.

Figure 5 is a transverse sectional view on 45 the plane indicated by the line 5—5 of Figure 3.

Figure 6 is a view partly in section and 50 partly in elevation of the solenoid showing the latter as effecting switch-retaining position.

Figure 7 is a view similar to Figure 6 but illustrating the switch-releasing position.

Figure 8 is a diagrammatic view of the 55 wiring.

Figure 9 is an elevational view of the modified form.

Figure 10 is a vertical sectional view on 60 the plane indicated by the line 10—10 of Figure 9.

The invention which embodies a combined signal and barrier comprises a transversely disposed element consisting of a top plate 10 strengthened on the underside by the longitudinally extending angles 11, the angles being 65 set in from the longitudinal edges of the

plate. The plate is disposed over a trench 12 formed in the roadway of masonry or concrete, the upper corners of the trench being protected by angle iron guards 14, the horizontal flanges of which are just below the surface of the roadway to permit the plate 10, when lowered to lie flush with the roadway, the plate being wider than the trench and the angle guards 14 serving as seats for 70 the side edges of the plate beyond the angles 11.

Spaced columns 15 and 16 are provided for supporting the transverse element and are in the form of channels of which that 75 constituting the column 15 is closed by a cover plate 17 and that constituting the column 16 is closed by the cover plate 18. The columns 15 and 16 are provided on the upper ends with ornamental caps 19 and are set in a foundation 20 in the roadway, the signalling element descending into 80 a trench 21 in said foundation when in inoperative position.

Extending longitudinally of the signalling 85 element beneath the top plate thereof and journaled in appropriate bearings thereon is a shaft 22 carrying at its extremities the pinions 23 meshing with racks 24 disposed within and secured to the columns, the inner faces of the columns being provided with slots 25 coextensive with the racks to provide clearance spaces for the shaft 22.

The two columns 15 and 16, in addition 90 to the slots 25, are provided with the side slots 26 adjacent the flanges of the angles to provide clearance spaces for the angles 11, these angles extending into the column 15 and through the column 16, projecting 95 laterally beyond the latter, as indicated at 27, and serving as a base for the motor 29, the latter being enclosed by a housing 30. The motor is operatively connected to the shaft 22 by means of a pinion 31 carried by the motor shaft and meshing with a spur gear 32 carried on the shaft 22. Obviously, 100 the rotation of the motor will elevate the transverse element as well as itself because of the pinions 23 meshing with the racks 24.

The signalling element is counterweighted, 105 each column being provided with a weight 33 with which cables 34 are connected, the cables being anchored to the angles 11 and trained over sheaves 35 in the upper ends 110 of the columns. The counterweights obviously act as a balance for the signalling element and its operating motor, so that the

work of the latter in elevating and lowering the signal is reduced to a minimum.

The control of the motor is effected by means of the spaced switches 36 and 37 mounted on the post 38 at the upper and lower ends of the latter, the post being set in the foundation and extending up into the motor case. These switches are normally impelled toward closed positions by the springs 39 and 40 and are shifted to open position by the arm 41 carried by the motor. A solenoid 42 has its core operatively connected with the switch 37 to retain it in open position in opposition to the spring 40.

Current for the motor is derived from the storage battery 43 housed in a suitable compartment in the foundation and one terminal of the storage battery is connected to one of the rails 44 as well as to one of the arms of the switch 37, as shown in the diagrammatic view by the lines 45 and 46 indicating the conductors. The rail 47 is connected to one of the arms of the switch 36 by a conductor 48 with which the solenoid 42 is in parallel. The opposite terminal of the battery 43 is connected to the remaining arms of the switches 36 and 37, as indicated by the conductors 49 and 50. The fixed contacts 51 and 52 of the switches 36 and 37 respectively are interconnected and also connected respectively with the field and armature of the motor 29, so that when one switch is closed, the direction of rotation of the motor is the reverse of that which takes place when the other switch is closed.

In the lowered position of the signal and barrier, the arm 41 carried by the motor is engaged with the arm 53 of the switch 37 and this switch 37 is therefore held in open position against the tension of the spring 40. The solenoid 42 is designed to retain the switch 37 in this open position in the elevating movement of the barrier and the signal and to this end the solenoid is provided with the pivotally mounted hook members 54 disposed on top of the solenoid at diametrically opposite sides of the latter. The hook members swing toward and from each other and when in mutual engagement, the noses 55 will permit the elevation of the arm 53 by the spring 40, since the arm is formed with an opening 56 through which the noses of the hook member may pass. With the arm depressed, as when it is engaged by the arm 41 carried by the motor, and the solenoid energized, the core 57 of the latter is elevated and the extension 58 carried thereby engages the two hook members and deflects them outwardly so that the noses 55 are in overhanging relation to the arms and the latter is held depressed despite the fact that the arm 41 is raised when the barrier and its actuating motor are elevated. The extension 58 is of generally tapering form, so that upon deenergization of the solenoid the core

is permitted to drop due to the action of the spring 41 tending to deflect the hook members inwardly because of the engagement of the upper face of the arm 53 with the inclined under edges 59 of the noses 55.

Stays 60 are provided on opposite sides of the roadway approaching the crossing, these stays being connected at one end to anchors 61 and the other end to the upper extremities of the columns 15 and 16. The stays are provided with resilient inserts 62 in the form of springs, so that in event of the barrier being subjected to a shock as by impact of an oncoming car the columns will not be displaced, the inserts providing suitable cushions.

The depending flange of one of the angles 11 is provided at uniformly spaced points with colored transparencies 63 while the barrier on the under face and between the angles 11 is provided with a lamp 64, the light from the latter shining through the transparencies 63 and the flange of the angle carrying the transparencies being inscribed at the center with the word "Stop" as indicated at 65.

In Figure 10 there is shown a modification of the invention for city use. In this construction the barrier consists of a cross-sectionally T-shaped member 70 of which the leg flange 71 enters a trench 72 formed in the roadway, the cross flange in the inoperative position lying flush with the roadway and seating upon angles 73 constituting corner guards for the trench. The signal is elevated by means of solenoids 74 of which the cores 75 are connected with the leg flange 71 of the barrier. That face of the leg flange that is presented to the approaching motorist when the barrier is elevated is inscribed with the word "Stop" as indicated at 76.

In the operation of the invention, the barrier is normally in the lower or unobstructing position, at which time the arm 41 carried by the motor is engaged with the arm 53 of the switch 37, retaining this switch in open position. The switch 36, however, is closed by the spring 39. Upon the approach of a train, on the latter entering the block with which the device is connected, a circuit is established on the battery 43 by the electrical connection of the rails 44 and 47 by the car wheels. Current then passes from the battery 43 to the motor 29 with which, when the switch 36 is closed, the solenoid 42 is in parallel. The solenoid is thus energized and the arm 53 of the switch 37 engaged so that the switch will be held open. The motor, with the switch 36 closed, will be rotated in the proper direction to elevate the combined signal and barrier and, when the prescribed height of the latter has been reached, the arm 41 will engage the switch 36 and open the latter, so that the motor is

thus deprived of current and the signal and barrier stands in the position in which it is left. The magnet 42, however, still remains energized and retains the switch 37 in open 5 position until the train shall have left the block and the circuit broken between the rails 44 and 47, when the solenoid 42 is deprived of current. The switch 37 is then released and moved to closed position by 10 the spring 40, the motor is supplied with current but its direction of rotation is changed so that the lowering movement is communicated to the barrier and signal and, when the latter has reached its position flush with 15 the roadway, the switch 37 is opened by the engagement of the arm 41 with the arm 53.

The invention having been described, what is claimed as new and useful is:

20 1. Apparatus for the purpose indicated comprising spaced columns, a barrier spanning said columns and movable vertically thereof, an actuating motor carried by the barrier, operative connections between the 25 motor and the columns for moving the bar-

rier upon rotation of the motor, and a remote control for the motor.

2. An appliance for the purpose indicated comprising spaced vertically disposed columns, a horizontal barrier spanning said 30 columns and movable longitudinally thereof, racks carried by the columns, a motor carried by the barrier, geared connections between the motor and the racks, and a remote control for the motor.

3. An appliance for the purpose indicated comprising spaced vertically disposed columns, a horizontal barrier spanning said 35 columns and movable longitudinally thereof, racks carried by the columns, a motor carried by the barrier, geared connections between the motor and the racks, counterweights housed in the columns, cables connecting the counterweights to the barrier and trained over guide pulleys carried at 40 the upper extremities of the columns, and a remote control for the motor.

In testimony whereof he affixes his signature.

GIROLAMO RAGUSA.
